UNITED STATES PATENT OFFICE.

MELBOURNE E. VEZIE, OF CEMENT, OKLAHOMA.

BURNER.

1,374,045.

Specification of Letters Patent.

Patented Apr. 5, 1921.

Application filed February 26, 1920. Serial No. 361,596.

To all whom it may concern:

Be it known that I, MELBOURNE E. VEZIE, a citizen of the United States, residing at Cement, in the county of Caddo and State 5 of Oklahoma, have invented certain new and useful Improvements in Burners, of which the following is a specification, reference being had to the accompanying drawings.

This invention relates to an improved gas 10 burner, and an object is to provide a device of this kind especially adapted for burning hot gas, receiving its heat from any suitable supply of steam or the like (not shown), in combination with means permitting the 15 requisite supply of air to insure a necessary mixture of combustible fuel to be burned at the end of the burner.

Another object resides in the provision of 20 a burner comprising inner and outer axially aligned tubes or casings, one in spaced surrounding relation to the other. The invention also embodies means to supply heated gas to be directed into and through the inner tube or casing, the surrounding air space between the inner and outer tubes or casings 25 being in communication with the inner tube, whereby an air supply drawn through the outer tube from one end thereof is injected toward and through the inner tube to provide a proper mixture to be lighted at one end of the inner tube.

A further object is to provide a burner of this kind wherein air to be mixed with the heated gas enters the burner and travels 35 along the inner tube to derive heat therefrom to insure a better combustible fuel.

While the design and construction at present illustrated and set forth is deemed preferable, it is obvious that as a result of a reduction of the invention to a more practical 40 form for commercial purposes, the invention may be susceptible to changes, and the right to these changes is claimed, provided they are comprehended within the scope of what 45 is claimed.

The invention comprises further features and combination of parts, as will be herein-after set forth, shown in the drawings and claimed.

50 In the drawings:—

Figure 1 is a longitudinal sectional view through the burner constructed in accordance with the invention;

Fig. 2 is a cross sectional view on line 55 2—2 of Fig. 1;

Referring more especially to the drawings, 1 and 2 designate inner and outer tubular casings, the latter being in surrounding spaced relation to the former, thereby providing an air chamber 3. The inner tubular 60 casing is open at both ends, as shown, and is provided with a gas burning chamber 4.

Suitable dowel pins 5 are threaded through the wall of the outer tubular casing and are also threaded into the wall of the 65 inner tubular casing, as indicated at 6 and 7. By means of these dowel pins, the inner tubular casing is supported rigidly within and with relation to the outer casing. One end of the inner tubular casing projects beyond the open end 8 of the outer casing. 70 The fuel as it passes through the gas burning chamber may be lighted at the point *a*, and as the fuel is burned the inner casing becomes thoroughly heated. As the gas and 75 air passes through the gas burning chamber, as indicated by the arrows *b*, it becomes thoroughly vaporized, for combustion at the point indicated at *a*.

One end of the outer casing 2 is closed 80 by the cap 9, which is threaded to the outer casing, as at 10, and a suitable tube or pipe 11 is designed to be connected to any suitable source of gas supply (not shown), and passes through the cap 9 of the outer casing, 85 and is provided with a perforated end 12. This end 12 protrudes partially into the inner end of the inner casing 1, in spaced relation from the marginal edge of said inner ends. The pipe or tube 11 is secured 90 in the wall of the cap 9 by means of the clamping nuts 13 and 14, which are threaded upon the tube and are forced jam against the opposite bosses of the cap 9.

In the operation, gas from any suitable 95 source of supply passes through the tube 11 and escapes at the perforated end 12. As the gas escapes into the gas burning chamber 4, air is drawn from the air chamber 3 through the end 15 of the inner casing, there 100 being an injection action of the air whereby the air may thoroughly mix with the escaping gas. Fresh air is drawn through the open end 8 of the outer casing, and as it passes through the chamber 3, it travels 105 along the wall of the inner casing 1 and derives heat therefrom, so as to mix with and volatilize the gas in the chamber 4.

In order to volatilize or vaporize the oil gas as it enters the tube 4 and also to insure 110

a better combustible mixture, steam from any suitable source is injected through the casing or tube 4 by means of the pipe or tube 11^a. This supply tube 11^a has its outer 5 end threaded so that a hose or pipe may be connected thereto, while its inner end has a right angular portion, which is perforated as shown at 11^c for spraying the steam into the chamber 4, thereby more thoroughly 10 atomizing the mixture. The tube or pipe 11^a passes through the wall of the section 2 of the outer casing of the burner and is held in place in the wall by the nuts 11^b. The heat in the burner will vaporize the oil and 15 when mixed with the air drawn into the chamber 4 as indicated by the arrows and when atomized by the steam, a suitable combustible gas is generated in the chamber, which becomes ignited and insures intense 20 heat.

The invention having been set forth, what is claimed as new and useful is:—

1. In a burner as set forth, inner and outer tubes, diametrically opposite radial means 25 at both ends of the inner tube for holding the former throughout its length in spaced relation to the latter, whereby the air drawn into the space between the two tubes may be heated as it enters the space and circulates 30 around the inner tube, the former having both ends open, the outer tube having an open end adjacent one of the open ends of the inner tube and having its other end closed spaced concentrically from the other 35 open end of the inner tube, the outer tube

comprising a pair of united sections, and a gas supply pipe engaged through the closed end of the outer tube and having a perforated end terminating adjacent to and partly within the inner end of the inner tube for injecting a supply of gas thereinto, acting to draw heated air from around the exterior of and forcing it into the inner tube, and means for adjustably holding the gas tube in the closed end of the outer tube, whereby the 40 inner perforated end of the gas tube may be adjusted relatively to the inner open end of the inner tube.

2. In a burner as set forth, inner and outer tubes, the former being open at both ends, 50 means for holding the inner tube concentrically spaced within the outer tube, one end of the outer tube being open, its other end being closed, a gas supply pipe engaged adjustably through the closed end and having 55 a perforated nozzle projecting partially within one of the open ends of the inner tube, thereby acting to draw air into the inner tube from around its exterior as the gas is injected into the inner tube, a steam 60 supply pipe adjustably mounted in the wall of the outer tube and projecting through the wall of the inner tube and terminating in a steam spray nozzle, for spraying steam into the inner tube, thereby thoroughly atomizing 65 the mixture.

In testimony whereof I hereunto affix my signature.

MELBOURNE E. VEZIE.
